UNITED STATES PATENT OFFICE.

CLAUDE C. MCLEAN, OF WULFFSOHN BAY, BRITISH COLUMBIA, CANADA.

LOG-LOADING BOOM.

1,249,153.

Specification of Letters Patent. Patented Dec. 4, 1917.

Application filed September 27, 1917. Serial No. 193,529.

To all whom it may concern:

Be it known that I, CLAUDE C. MCLEAN, a citizen of the United States of America, residing at Wulffsohn Bay, in the Province of 5 British Columbia, Dominion of Canada, have invented certain new and useful Improvements in Log-Loading Booms; and I do hereby declare the following to be a full, clear, and exact description of the invention, 10 such as will enable others skilled in the art to which it appertains to make and use the same.

This invention relates to loading apparatuses, and has particular reference to 15 booms for loading logs upon logging trains.

The object of the invention is to provide an improved form of log loading boom, which will provide greater safety for the operators and also to the cars which are being loaded. Furthermore, the improved boom is designed to provide more rapid and efficient handling of the logs. It is well known in the art that in the use of the booms which are at present employed, the 20 loading hooks frequently pull out of the log and swing around to the jeopardy of the loaders. Some loading devices are equipped with tongs, but as they are fastened on long lines, they are equally as dangerous as hooks 25 whenever a log gets beyond control. By the use of the present device, the tongs are fastened to a crotch line, after the line is passed through a crotch line block, thereby giving a much shorter sweep to the line, in 30 the event that they pull loose from the logs. Furthermore, the strain on the line, in the event that the tongs pull out of the logs, runs the tongs up to the boom, where there is no danger of their swinging about to endanger 35 the position of the loading crew. Furthermore, by the use of my improved device, I provide against the breakage of cars which constitutes a considerable factor in the loading operations as carried out with the loading 40 devices at present in use, since by the use of the latter, the loading engineer frequently loses control of the long lines from which the logs are suspended, so that the latter swing against the cars and seriously 45 damage them.

Another important factor in connection with the use of my invention rises from the fact that the log is always positioned parallel with the car, so that it is not necessary 55 for the engineer to wait for the log to swing

"square" with the car before lowering it into place, thus avoiding a considerable loss of time.

With the above objects in view, and such others relating to the details of construction 60 as may hereinafter appear, my invention will now be fully set forth and described, reference being had to the accompanying drawings.

In the drawings:—

Figure 1 is a perspective view showing the manner of use of my invention,

Fig. 2 is a plan view of the boom,

Fig. 3 is an enlarged view of one of the boom arms,

Fig. 4 is an enlarged detail view of the boom mounting,

Fig. 5 is an enlarged view of a slack take-up carriage, and

Fig. 6 is an enlarged view of a counter-weight carriage.

Referring more particularly to the drawings, 1 represents a boom whose pivotal end is incased in side straps 2 provided with the bearing openings 3 extending transversely of 80 the boom. Said bearing openings 3 receive a horizontal pin 4 whose ends are borne by a boom block 5 which is bifurcated to receive the end of the boom therebetween. The boom block 5 is also provided with a vertical 85 bearing opening 6 within which a pin 7 is received, the latter being supported above and below the block 5 in the eyes 8 of a pair of pins 9 which are adapted to be driven into a tree, or other vertical spar 10 to provide for the horizontal swinging of the boom. In order to prevent the swaying of the spar tree or other support, guy-lines 11, 12 and 13 are carried out at suitable angles 90 from the tree and attached to convenient stumps, stakes or other fastenings.

The free end of the boom 1 is provided with four laterally extended boom arms 14 arranged in pairs, one near the extremity of the boom, and the other approximately a 100 log length to the rear of the first mentioned pair. Each of the arms 14 comprise a vertically disposed plate which extends from a base plate 15 and is braced to the latter by means of triangular webs 16. The extremities of the arms 14 are provided with shackles 17 for the connection of lines or other appurtenances. Between the arms 14, the boom is provided with a haulback block 18 through which a haulback line 20 is 110

passed. One end of the haulback line 20 is connected to the guy line 13 by means of a suitable fitting 21. The bight is then passed through the block 18, thence through the haulback blocks 22 and 23 on the guy line 13 and the spar 10 respectively, and thence to the drum 24 of the usual donkey engine. A loading line 25 extending from the second drum 26 extends through a block 27 strapped to the upper end of the spar tree, thence through a second block 28 suitably positioned upon the guy line 12, and then at a shackle 29 is subdivided into a pair of crotch lines 30, one of which is connected to a forward arm 14, and the other of which is connected to a rear arm 14 upon the opposite side. At their respective arms 14, the crotch lines pass through blocks 31 and carry at their free ends the tongs 32.

Attached to the same arms 14 to which the crotch lines are connected, are the guy lines 33 which connect to a common shackle 34 strapped to the upper end of the spar tree, adjacent the connection of the guy lines 11, 12 and 13. Upon one of the guy lines 33, a slack take-up carriage 35 is mounted and is connected by means of a line 36 with the shackle 29 of the loading line.

Also connected to the forward end of the boom 1, is a counter-weight line 37, which passes over a block 38 connected to the guy line 12 extending beyond the end of the boom, and then connects to a counter-weight carriage 39 which rides upon the guy line 12, and carries a suitable counter-weight 40.

In the operation of the boom which has been described, the crotch lines 30 are connected to the arms 14 diagonally across the boom in accordance with the direction which the track 41 lies with respect to the boom and the log pile. Thus, in Fig. 2, the middle of the track underlies the forward right hand arm 14 and the rear left hand arm 14 so that a log suspended from these arms 45 would lie parallel with the track and consequently parallel to a car upon which the log is to be loaded. Obviously, if the log pile lay upon the opposite side of the spar 10, so that the boom must be swung down track, instead of in the direction indicated in Fig. 2, the opposite arms 14 would be employed to guide the crotch lines. The rigging which has been described as necessary for the successful operation of the improved boom may be modified to meet the exigencies of the particular locality and conditions where the boom is employed, but in each case must include the crotch lines 30. It will be evident that logging operation carried out with the aid of my improved structure will progress with greater speed and safety than would be possible by the use of the ordinary booms now in use.

What I claim as my invention is:

1. A hoisting apparatus, comprising in combination with a spar, a boom pivoted to the spar for vertical and horizontal movement, means for operating the boom vertically, off-set members carried by the boom at different distances from its free extremity, and loading lines operative in unison from the extremities of said off-set elements.
2. A boom for logging operations, comprising in combination with a boom spar, pairs of laterally extended arms carried by the boom at spaced intervals from its free extremity, and interchangeable loading line connections carried by the free ends of the arms.

In testimony whereof, I affix my signature in the presence of two witnesses.

CLAUDE C. MCLEAN.
